UNITED STATES PATENT OFFICE.

WILLIAM H. PRITCHETT, OF CARTERSVILLE, GEORGIA.

AUTOMATIC MACHINE-GUN.

1,297,240.

Specification of Letters Patent. Patented Mar. 11, 1919.

Application filed December 22, 1916. Serial No. 138,525.

To all whom it may concern:

Be it known that I, WILLIAM H. PRITCHETT, a citizen of the United States, residing at Cartersville, in the county of Bartow and State of Georgia, have invented certain new and useful Improvements in Automatic Machine-Guns; and I do hereby declare the following to be a full, clear, and exact description of the invention, such as will enable others skilled in the art to which it appertains to make and use the same.

My invention relates to improvements in machine guns, and is intended to provide a piece which may be fired either automatically or single shot, and either from the shoulder from a suitable rest, or from a mount, and in which there is no positive lock to the reciprocating breech bolt when in the firing position; but the mass of the breech bolt and the parts carried thereby is such that, together with the compressive force of the main spring sufficient support is furnished to the base of the cartridge case to enable the gun to be fired and the projectile to clear the muzzle before the breech bolt has moved an appreciable distance to the rear.

The rearward movement of the massive breech bolt is not only taken care of by compressing the main, or return, spring, but is also arrested by a pneumatic dash pot arrangement, mounted on the rear end of the receiver, as will be hereinafter more fully described.

Incident to the return of the breech bolt to the rearward position, the empty cartridge case is extracted and ejected.

Certain means for cocking the piece by hand and for locking same in the single shot or firing position are also provided.

My invention is especially intended to provide an automatic gun having very few parts, which is of simple and rugged construction, and which is not so apt to get out of order as are the machine guns with the multiplicity of parts now generally in use.

These and the other details of the invention will be more fully understood after reference to the accompanying drawings, in

which similar parts are indicated by similar reference symbols throughout the several views.

Figure 1 is a side elevation showing the complete piece as seen from the right;

Fig. 2 is a similar view showing the piece as seen from the left;

Fig. 3 is a view on a larger scale of the breech end of the piece shown in Fig. 2, parts of the mechanism being shown in dotted lines;

Fig. 3^a shows the barrel end of the piece with the inclosing casing, which, when joined to Fig. 3, would constitute the whole piece;

Fig. 4^a shows the barrel end of the piece, the breech end of which is shown in Fig. 4, both being plan views;

Fig. 5 is a view of the barrel and casing looking in the muzzle, as seen from the left of Fig. 3^a;

Fig. 6 is a view of the barrel and casing, as seen from the right of Fig. 3^a, and looking toward the front;

Fig. 7 shows a central section through the receiver made by the horizontal plane 7—7 of Fig. 3, parts being shown in elevation, and the breech bolt being shown in the forward or firing position;

Fig. 7^a shows a similar section through the barrel end of the piece, this section being taken along the line 7^a—7^a of Fig. 8^a and looking in the direction of the arrows;

Fig. 8 is a central vertical section through the receiver along the line 8—8 of Fig. 4, parts being shown in elevation, and the breech bolt being shown in its rearmost position;

Fig. 8^a shows a similar section through the barrel end of the piece, this section being taken on the line 8—8 of Fig. 7^a;

Fig. 9 shows a section along the line 9—9 of Fig. 8^a, and looking in the direction of the arrows;

Fig. 10 shows a section along the line 10—10 of Fig. 8^a, and looking in the direction of the arrows;

bolt, with the extractor attached thereto, detached from the gun;

Fig. 12 shows a section along the line 12—12 of Fig. 3, looking in the direction of the arrows;

Fig. 13 is a detail showing the engagement of the trigger and sear;

Fig. 14 shows a section through the feed hopper along the line 14—14 of Figs. 1, 2, 3, 10 and 8, showing the cartridges being supplied to the gun;

Fig. 15 is a side elevation of the central portion of the piece showing the locking lever in the single shot position;

Fig. 16 is a similar view showing the locking lever in the position for automatic firing;

Fig. 17 is a plan view;

Fig. 18 is a rear elevation of the pneumatic dash pot arrangement, attached to the breech end of the receiver; and

Fig. 19 shows a horizontal section through Fig. 18 along the line 19—19, and looking in the direction of the arrows.

25 The piece comprises the following principal parts:

The receiver A carried by the stock A', the barrel B secured to the receiver, having its casing C spaced away therefrom, the breech bolt D with its cocking arm D', the main spring E, the firing pin F, the extractor G, the ejector H, the locking lever I, the lever spring I', the trigger J, the sear K, the pneumatic dash pot M, and the feed hopper P. These, with any suitable form of front and rear sights, constitute all of the essential elements of the piece.

In Figs. 1 and 2 I have shown a sling strap Q provided.

40 Having thus stated generally the several parts of the piece, I will now describe the same more in detail.

The receiver A is provided on the front end with internal screw threads 1, adapted to engage the external screw threads 2 on the breech of the barrel; and the receiver is chambered to receive the breech bolt and main spring and parts carried thereby, and is provided with an annular shoulder 3 to engage the corresponding shoulder 4 on the breech bolt D when the latter is in the forward position as shown in Fig. 7. The receiver is also provided with the guide slot 5 for the cocking arm D', with the ejector slot 6 and with the opposite slot 7, in which the ejector H is pivoted. The receiver is also provided with the feed opening 9 beneath the hopper P, see Fig. 8.

60 The barrel B is screwed to the forward end of the receiver and is provided with a plurality of radially disposed lugs 11, to which the casing C is attached, as by means of the screws 12. This casing extends some-

what beyond the muzzle of the gun so that when the gun is fired, the powder gases will 65 suck air through the air space between the barrel and the casing, and will thus cool the barrel.

The front sight arm 13 is connected to the barrel near its muzzle and projects out 70 to one side thereof, as shown in Fig. 4^a, and the sight 14 projects beyond and to one side of the casing and in line with the rear sight 15, which is carried by the lug 16, projecting from the side of the barrel near the 75 breech, as shown in Figs. 4^a and 10.

The breech bolt D is perforated axially as at 20 (see Fig. 7) to receive the firing pin F; and its body portion 21 is shouldered as at 22 to engage the main spring E. The 80 heel of the breech bolt 23 is reduced in diameter and terminates in the screw cap 24, which screw cap is perforated as at 25 to permit the escape of air therethrough; and this cap serves to limit the rearward 85 travel of the firing pin and also protect the bore 20 through the breech bolt from taking in any foreign matter which would be likely to impair the free movement of the firing pin.

90 The forward end of the body portion 21 of the breech bolt is shouldered as at 4, as already described, to engage the shoulder 3 in the receiver when the breech bolt reaches the forward position; and the forward end 95 of the breech bolt carries the extractor G in the form of a leaf spring having a claw 26 and the cam face 27. When the breech bolt is driven to the rear by the force of the powder gases, this cam face 27 strikes the 100 cam arm 28 of the ejector H and causes the ejector to impart a quick blow to the cartridge case, throwing said case through the opening 6.

105 The head of the breech bolt should be of no greater vertical diameter, preferably of less diameter than the rim of the cartridge case, for when the bolt moves to the rear both the bolt and the empty cartridge case pass under the lower cartridge. The lower 110 cartridge then drops into the receiver in front of the bolt. On again moving forward the bolt shoves the lower cartridge into its firing seat, the second cartridge (which now becomes the lower) riding on top of the bolt. 115 It is for this reason only that the vertical diameter of the forward portion of the bolt can not be greater than the diameter of the base of the cartridge case, otherwise the bolt in its forward motion would take against 120 more than one cartridge.

125 This obviates the necessity for any mechanical device for delivering the cartridges *seriatim* from the magazine hopper, which is one of the chief objections to the feed mechanism of all the automatic guns now

in use. The "seriatim" feed mechanism is invariably complicated, requiring numerous small and delicate parts.

The cocking arm D', carried by the breech bolt, reciprocates in the guide groove 5.

The firing pin F is in the form of a long rod, mounted in and passing through the longitudinal axis of the breech bolt. It is provided with a notch 30 (see Figs. 7 and 8),

10 adapted to engage the claw 31 of the firing pin latch 32 (see Fig. 8), which latch is pivoted as at 33, and has an arm 34 normally pressed outward by the spring 35 so that when the firing pin is in the rearward position, having its rear end bringing up against the inner face of the screw cap 24, the claw 31 will engage in the notch 30, and will hold the firing pin against forward movement, as shown in Fig. 8.

20 This arm 34 travels in a guide groove 36 in the inner wall of the receiver, as shown in Fig. 8; and when the breech bolt is in the forward position, this arm 34 will engage the cam face 37 at the end of said groove 36, 25 and will trip the claw 31 out of engagement with the notch 30, permitting the firing pin to fly forward of its own inertia, its forward motion being arrested by the pin bringing up against the primer of the cartridge case.

30 In order to prevent the firing pin from being thrown out of its seat in the breech bolt after the last cartridge has been fired, I provide the tapered shoulders 20° (see Figs. 7 and 8) at the forward end of the bore 20 35 in the breech bolt, which will arrest the forward movement of the firing pin in the breech bolt after the point of the pin has projected forward the requisite distance for exploding the primer.

40 The piece is cocked by pulling the cocking arm D' backward against the action of the spring E, which would cause the catch 40 of the locking lever I to engage said cocking arm, as shown in Fig. 15. This locking lever 45 is pivoted as at 41 to the side of the receiver and has an arm 42, which is pressed upward by the spring I' against the stop 43.

As the breech bolt is moved to the rear either under the action of the cocking arm 50 D' or the pressure of the powder gases, this cocking arm D' will wedge up the cam face 44 of the cocking lever until the cocking arm has reached the position shown in Fig. 15, when the spring I' will cause the catch 40 to 55 snap in front of the cocking arm and will hold the breech bolt in the rearward position until said locking lever is tripped, which may be done by pressing down on the arm 42. This is the position for single shot firing. 60 When, however, it is desired to fire automatically, after the piece has been cocked the first time; the latch 45 may be turned from the position shown in Fig. 15 to that

shown in Fig. 16 when the catch 46 will engage the end of the lever arm 42 and will hold the catch 40 out of engagement with the cocking arm D', the parts then being in the position shown in Fig. 16. When the parts are in this position, the breech bolt can be reciprocated indefinitely rearward under the pressure of the powder gases and forward under the pressure of the main spring.

The trigger and sear are shown in Figs. 8 and 13.

The sear K is pivoted to the receiver at 75 50, and has a lug 51 projecting upwardly therefrom, which passes through an opening 52 in the receiver and projects into the line of travel of the breech bolt except when thrown out of engagement by the trigger. 80

The sear terminates rearwardly in the sear spring 54, which normally throws the lug 51 into the engaging position.

The trigger J is pivoted as at 60 to lugs 61 on the receiver, and is provided with an arm 85 61 adapted to press up on the sear spring 54, and to pull the lug 51 clear of the breech bolt. Thus the parts being in the position shown in Fig. 8, if the trigger be pulled backward, the breech bolt will be released 90 and will fly forward under the action of the spring E; and it will be free to reciprocate backward and forward as long as the pull on the trigger is continued.

Thus, the gun will continue firing automatically as long as the trigger is pulled and the ammunition supply is maintained. The trigger and sear are shown in the position for automatic firing in Fig. 16.

To control the rearward movement of the 100 breech bolt under the pressure of the powder gases, I provide not only the usual return spring E; but also a pneumatic dash pot arrangement M, shown in Figs. 3, 4, 7, 8, and in detail in Figs. 17 to 19. This comprises 105 a hollow block 70 secured to the receiver in any convenient way as by means of the union 71, which block is provided with a chamber 72, adapted to fit the screw cap 24 on the heel of the breech block as shown in Fig. 8. 110 This block has an opening 73 in its rear end, which is closed by the check valve 74, whose stem 75 projects through said openings 73. This check valve is normally held on its seat by the spring 76, whose tension may be adjusted by the lock nuts 77.

When the breech bolt is thrown back violently, as by the pressure of the powder gases, after the gun has been fired, the air in the receiver in rear of the breech bolt will be 120 forced backward, and will be compressed, and a part of it will be trapped in the chamber 72; and this air will be highly compressed and will serve as a dash pot not only to check the backward movement of the breech bolt, 125 but its elasticity will also assist the main

spring E in the initial forward movement of the breech bolt, thus relieving the shock of the reverse movement of the breech bolt from the rearward to the forward direction.

5 In case the pneumatic pressure should become too great, I provide a relief valve 78, controlling the escape passage 79 (see Figs. 7 and 19). This relief valve may be set at the desired position and clamped thereat by 10 means of the set screw 80 (see Figs. 17 and 18) engaging the head 78^a of the relief valve 78.

By adjusting the opening in the escape passage 79, the maximum pneumatic pressure in the chamber 72 may be regulated as desired.

After the heel of the breech bolt leaves the chamber 72, and the breech bolt continues to fly forward, there will be a partial 20 vacuum created in the rear end of the receiver and the check valve 74 will be moved off its seat against the action of the spring 76, and air will rush in to supply the loss of air that has escaped through the 25 relief passage 79.

The ammunition may be supplied to the piece in any convenient way; but I prefer to use a feed hopper of the shape shown in Figs. 3, 4, 8 and 14, in which the sides 30 81 and 82 of the hopper taper downward to a narrow throat 83 and in which the two sides are provided with staggered inclined surfaces 84, 85, 86, 87, 88 and 89, which tend to cause the cartridges to feed downward 35 toward the throat 83 without becoming jammed in the hopper. The cartridges are fed downward by their own weight.

To prevent cartridges in the hopper from feeding to the gun except when desired, I 40 provide a cut-off gate or blade 90 projecting into the throat of the hopper, as shown in Fig. 14. This gate is secured to a leaf spring 91, pivoted as at 91 to the side of the hopper, and projecting somewhat beyond 45 the edge of the hopper, as shown at 93, in Figs. 1, 2, and 8. By bringing this gate out of its slot and letting it rest against the outside of the hopper, the cartridges will fall down quickly by gravity; but by bringing 50 the gate back into the slot and allowing it to project into the hopper, it will stop the further downward feed of the cartridges.

Thus when it is desired to suspend firing 55 temporarily the gate 90 is thrown to the closed position. The cartridges beneath same will be fired automatically and the empty shells ejected, leaving the bottom cartridge in the hopper resting on said 60 gate and at a distance from the breech bolt when it returns to the closed position. Since the head of the breech bolt is apt to be highly heated incident to the previous rapid firing of the piece, the fact that the

lower cartridge in the hopper is entirely 65 clear of contact with the hot breech bolt will prevent any danger from premature explosion of said cartridge, due to the proximity of the heated head of the breech bolt.

In various automatic guns now in use, 70 when firing is arrested, before the feed supply is exhausted, the last cartridge rests on the head of the breech bolt, and there is more or less danger from premature explosion, due to the heat from the breech bolt 75 igniting the powder charge in the cartridge.

The hopper P is hinged as at 100 so as to be swung back along the top of the receiver when the gun is being transported, or is not adjusted for firing. Any suitable 80 means may be provided for locking it in the vertical position, when desired, such as the removable pin 101.

The hopper may be provided with a suitable cover 94 pivoted to one side thereof as 85 at 95, and secured to the other side thereof by the spring catch 96.

When the hopper is swung backward and rests on the top of the receiver the cover 94 and gate 90 will prevent the cartridges 90 from falling out of the hopper.

The operation of the device is as follows:

Suppose the hopper to be supplied with cartridges, and it is desired to fire single 95 shots, see that the gate 90 is swung clear of the throat of the hopper and that the latch 45 is in the disengaged position shown in Fig. 15, and cock the piece by hand, then pull back on the trigger releasing the sear, and the breech bolt will fly 100 forward under the action of the main spring E, the lower cartridge in the feed chamber will be pressed forward into the cartridge chamber of the gun, and the claw of the extractor 26 will be forced under the rim 105 of the cartridge case. As soon as the breech bolt reaches the closed position, the firing pin latch will be automatically released and the firing pin will fly forward under its own inertia, striking the primer and firing 110 the cartridge.

As the projectile flies forward through the bore, the pressure of the powder gases will be exerted on the far greater mass of the breech bolt and the parts carried thereby, 115 and the breech bolt will begin to move rearward about the time the projectile leaves the bore. The extractor will draw the empty cartridge case rearward until its cam face 27 strikes the shoulder arm 28 of the ejector 120 H, when the ejector will flip the empty cartridge case out through the opening 6 in the side of the receiver. The breech bolt in its rearward movement, carries with it the firing pin, also compresses the main spring 125 E, and also the air in the chamber 72 as hereinbefore described.

After reaching its rear limit of travel, the

breech bolt will be started forward again by the initial impulse of the pressure by the compressed air and the pressure of the spring E, and will continue its forward movement until the cocking arm D' engages the catch 40 on the locking lever I, as shown in Fig. 15. At this time, the further forward movement of the breech bolt will be arrested and the firing pin will be held by its latch 32, the parts then being slightly in rear of the position shown in Fig. 8.

To fire again, hold the cocking arm to the rear, press down on the lever arm 42 and allow the cocking arm to move slightly forward. This allows the catch 40 to ride on top of the cocking arm and at the same time the sear arm 51 will take in its notch in the breech bolt at the shoulder 4. The arm 51 alone is now holding the breech bolt to the rear. Now pull the trigger and the gun will fire a single shot, the breech bolt, on recoil, being again locked in its rear position by the latch 40. This cycle of operations may be repeated indefinitely.

For automatic firing, suppose the parts be at rest and the hopper provided with cartridges, set the locking lever in the position shown in Fig. 16, and cock the piece by hand, by pulling backward on the cocking arm D', the sear will then be in the position shown in full lines in Fig. 8 and in dotted lines in Fig. 15; now pull on the trigger and release the sear, as shown in Fig. 16; and as long as the trigger is pulled backward and the hopper supplied with cartridges, the automatic firing will continue.

The relief valve 78 should be so adjusted that the pneumatic pressure in the dash pot chamber will bring the breech bolt to a stop just before the rear end of the breech bolt brings up against the check valve 74.

The facility of the opening of the check valve 74 of the pneumatic dash pot may be increased or decreased by easing up or screwing down on the lock nut 77, on the valve stem 75, thus varying the tension of the spring 76.

Special advantages claimed for this piece are:

I. Simplicity of construction, there being no delicate or complicated mechanism to break or get out of adjustment, thus practically eliminating jams, the chief difficulty with machine guns now in use.

II. The small number of moving parts, the principal moving parts being the breech bolt, the firing pin, the firing pin locking lever, the main spring, and the ejector.

III. The breech bolt moves longitudinally in a straight line and does not have any turning motion for locking, therefore, it is possible to secure greater rapidity of automatic fire.

IV. The automatic fire may be continued,

it being unnecessary to cease firing to fill up the magazine hopper.

V. The gun can be easily operated by one man.

VI. The gun can be fired from the shoulder without a rest, although a rest is preferable.

VII. There is no possibility of a premature explosion, since the cartridge must be fully seated before it can be reached by the firing pin and fire.

VIII. By having spare barrels with their cases, sights, etc., the barrel can be quickly changed in case it becomes overheated; but the gun may be fired a large number of rounds without the barrel being overheated, owing to the air cooling arrangement shown.

IX. There is very slight recoil and very little shock at the end of the rearward stroke of the heavy breech bolt, thus contributing greatly to the accuracy of aim and direction of fire.

X. The ballistic qualities of the gun are of very high order.

XI. The trigger and sear arrangement, forming a part of the firing mechanism, are extremely simple and the firing pin needs no spring to drive it forward, and no separate means for restoring the firing pin to the proper position is needed.

It will be obvious that various modifications in the herein described construction and combination and arrangement of parts might be made without departing from the spirit of my invention.

Having thus described my invention, what I claim and desire to secure by Letters Patent of the United States is:

1. In an automatic gun, the combination with a receiver, of a reciprocating breech bolt comprising a single piece slidably mounted therein adapted to be forced rearward by the powder gases, a main spring mounted in said receiver directly in rear of said breech bolt for returning said breech bolt to the closed position, a firing pin slidably mounted in said breech bolt, means for locking said firing pin to said breech bolt during the reciprocating movement of said bolt, and means for automatically releasing said firing pin and allowing it to fly forward under its own inertia when the breech bolt reaches the closed position, substantially as described.

2. In an automatic gun, the combination with a receiver, of a reciprocating breech bolt comprising a single piece slidably mounted therein adapted to be forced rearward by the powder gases, a main spring mounted in said receiver directly in rear of said breech bolt for returning said breech bolt to the closed position, a firing pin slidably mounted in said breech bolt, means for locking said firing pin to said breech bolt

- 6 during the reciprocating movement of said bolt, and means for automatically releasing said firing pin and allowing it to fly forward under its own inertia when the breech 5 bolt reaches the closed position, with a pneumatic dash pot mounted at the end of the receiver and adapted to arrest the rearward movement of said breech bolt, substantially as described.
- 10 3. In an automatic gun, the combination with a receiver, of a reciprocating breech bolt slidably mounted therein adapted to be forced rearward by the powder gases, a main spring mounted in said receiver for returning said breech bolt to the closed position, a firing pin slidably mounted in said breech bolt, means for locking said firing pin to said breech bolt during the reciprocating movement of said bolt, and for automatically 15 releasing said firing pin and allowing it to fly forward under its own inertia when the breech bolt reaches the closed position, comprising a spring impressed latch carried by said breech bolt and having a catch 20 adapted to engage said firing pin, and an arm adapted to be tripped by said receiver as the breech bolt nears the forward limit of its travel, substantially as described.
4. In an automatic gun, the combination 30 with a receiver, of a reciprocating breech bolt slidably mounted therein adapted to be forced rearward by the powder gases, a main spring mounted in said receiver for returning said breech bolt to the closed position, a firing pin slidably mounted in said breech bolt, means for locking said firing pin to said breech bolt during the reciprocating movement of said bolt, and for automatically 35 releasing said firing pin and allowing it to fly forward under its own inertia when the breech bolt reaches the closed position, comprising a spring impressed latch carried by said breech bolt and having a catch 40 adapted to engage said firing pin, and an arm adapted to be tripped by said receiver as the breech bolt nears the forward limit of its travel, with a pneumatic dash pot mounted at the end of the receiver and adapted to arrest the rearward movement 45 of said breech bolt, substantially as described.
5. In an automatic gun, the combination 50 with a receiver, of a reciprocating breech bolt slidably mounted therein adapted to be forced rearward by the powder gases, a main spring mounted in said receiver for returning said breech bolt to the closed position, a firing pin slidably mounted in said breech bolt, means for locking said firing 55 pin to said breech bolt during the reciprocating movement of said bolt, means for automatically releasing said firing pin and allowing it to fly forward under its own inertia when the breech bolt reaches the closed 60 position, an extractor carried by said breech bolt, and provided with a cam face, and an ejector pivoted in said receiver, and having a short arm adapted to be struck by said cam face, substantially as described.
6. In an automatic gun, the combination 70 with a receiver, of a reciprocating breech bolt slidably mounted therein adapted to be forced rearward by the powder gases, a main spring mounted in said receiver for returning said breech bolt to the closed position, a firing pin slidably mounted in said breech bolt, means for locking said firing pin to said breech bolt during the reciprocating movement of said bolt, means for automatically 75 releasing said firing pin and allowing it to fly forward under its own inertia when the breech bolt reaches the closed position, an extractor carried by said breech bolt, and provided with a cam face, and an ejector pivoted in said receiver, and having a short arm adapted to be struck by said cam face, with a pneumatic dash pot mounted at the end of the receiver and adapted to arrest the rearward movement 80 of said breech bolt, substantially as described.
7. In an automatic gun, the combination 85 with a receiver, of a reciprocating breech bolt slidably mounted therein adapted to be forced rearward by the powder gases, a main spring mounted in said receiver for returning said breech bolt to the closed position, a firing pin slidably mounted in said breech bolt, means for locking said firing pin to said breech bolt during the reciprocating movement of said bolt, means for automatically 90 releasing said firing pin and allowing it to fly forward under its own inertia when the breech bolt reaches the closed position, a sear pivoted to the receiver, and having an arm projecting into the path of the breech bolt, and a spring arm, and a trigger piece having an arm adapted to engage said spring arm of the sear, and to release said sear from engagement with said 95 bolt, substantially as described.
8. In an automatic gun, the combination 100 with a receiver, of a reciprocating breech bolt slidably mounted therein adapted to be forced rearward by the powder gases, a main spring mounted in said receiver for returning said breech bolt to the closed position, a firing pin slidably mounted in said breech bolt, means for locking said firing pin to said breech bolt during the reciprocating movement of said bolt, means for automatically 105 releasing said firing pin and allowing it to fly forward under its own inertia when the breech bolt reaches the closed position, a sear pivoted to the receiver, and having an arm projecting into the path of the breech bolt, and a spring arm, and a trigger piece having an arm adapted to engage said spring arm of the sear, and to release said sear from engagement with said 110 bolt, substantially as described.
- 115 9. In an automatic gun, the combination with a receiver, of a reciprocating breech bolt slidably mounted therein adapted to be forced rearward by the powder gases, a main spring mounted in said receiver for returning said breech bolt to the closed position, a firing pin slidably mounted in said breech bolt, means for locking said firing pin to said breech bolt during the reciprocating movement of said bolt, means for automatically 120 releasing said firing pin and allowing it to fly forward under its own inertia when the breech bolt reaches the closed position, a sear pivoted to the receiver, and having an arm projecting into the path of the breech bolt, and a spring arm, and a trigger piece having an arm adapted to engage said spring arm of the sear, and to release said sear from engagement with said 125 bolt, substantially as described.
- 130 10. 3. In an automatic gun, the combination with a receiver, of a reciprocating breech bolt slidably mounted therein adapted to be forced rearward by the powder gases, a main spring mounted in said receiver for returning said breech bolt to the closed position, a firing pin slidably mounted in said breech bolt, means for locking said firing pin to said breech bolt during the reciprocating movement of said bolt, means for automatically releasing said firing pin and allowing it to fly forward under its own inertia when the breech bolt reaches the closed position, an extractor carried by said breech bolt, and provided with a cam face, and an ejector pivoted in said receiver, and having a short arm adapted to be struck by said cam face, substantially as described.

ment with said bolt, with a pneumatic dash pot mounted at the end of the receiver and adapted to arrest the rearward movement of said breech bolt, substantially as described.

9. In an automatic gun, the combination with a receiver, of a reciprocating breech bolt slidably mounted therein adapted to be forced rearward by the powder gases, a main spring mounted in said receiver for returning said breech bolt to the closed position, and a pneumatic dash pot mounted at the end of the receiver and adapted to arrest the rearward movement of said breech bolt, said dash pot comprising a hollow block secured to the rear end of the receiver and having a chamber adapted to fit the heel of the breech block, and a spring impressed check valve normally closing said chamber against the escape of air therefrom, but permitting the influx of air as the breech bolt flies forward from its rearmost position, substantially as described.

10. In an automatic gun, the combination with a receiver, of a reciprocating breech bolt slidably mounted therein adapted to be forced rearward by the powder gases, a main spring mounted in said receiver for returning said breech bolt to the closed position, and a pneumatic dash pot mounted at the end of the receiver and adapted to arrest the rearward movement of said breech bolt, said dash pot comprising a hollow block secured to the rear end of the receiver and having a chamber adapted to fit the heel of the breech block, and a spring impressed check valve normally closing said chamber against the escape of air therefrom, but permitting the influx of air as the breech bolt flies forward from its rearmost position, the said chamber being also provided with a relief passage, and a relief valve controlling the opening through said relief passage, substantially as described.

11. In an automatic gun, the combination with a receiver, of a reciprocating breech bolt slidably mounted therein adapted to be forced rearward by the powder gases, a main spring mounted in said receiver for returning said breech bolt to the closed position, a firing pin slidably mounted in said breech bolt, means for locking said firing pin to said breech bolt during the reciprocating movement of said bolt, means for automatically releasing said firing pin and allowing it to fly forward under its own inertia when the breech bolt reaches the closed position, and a pneumatic dash pot mounted at the end of the receiver and adapted to arrest the rearward movement of said breech bolt, said dash pot comprising a hollow block secured to the rear end of the receiver and having a chamber adapted to fit the heel of the breech block, and a spring impressed check valve normally closing said chamber against

the escape of air therefrom, but permitting the influx of air as the breech bolt flies forward from its rearmost position, substantially as described.

12. In an automatic gun, the combination with a receiver, of a reciprocating breech bolt slidably mounted therein adapted to be forced rearward by the powder gases, a main spring mounted in said receiver for returning said breech bolt to the closed position, a firing pin slidably mounted in said breech bolt, means for locking said firing pin to said breech bolt during the reciprocating movement of said bolt, means for automatically releasing said firing pin and allowing it to fly forward under its own inertia when the breech bolt reaches the closed position, and a pneumatic dash pot mounted at the end of the receiver and adapted to arrest the rearward movement of said breech bolt, said dash pot comprising a hollow block secured to the rear end of the receiver and having a chamber adapted to fit the heel of the breech block, and a spring impressed check valve normally closing said chamber against the escape of air therefrom, but permitting the influx of air as the breech bolt flies forward from its rearmost position, the said chamber being also provided with a relief passage, and a relief valve controlling the opening through said relief passage, substantially as described.

13. In an automatic gun, the combination with a receiver, of a reciprocating breech bolt slidably mounted therein adapted to be forced rearward by the powder gases, a main spring mounted in said receiver for returning said breech bolt to the closed position, a firing pin slidably mounted in said breech bolt, a spring impressed latch for locking said firing pin to said breech bolt during the reciprocating movement of said bolt, and an arm on said latch adapted to engage a cam face on the receiver for automatically releasing said firing pin and allowing it to fly forward under its own inertia when the breech bolt reaches the closed position, substantially as described.

14. In an automatic gun, the combination with a receiver, of a reciprocating breech bolt slidably mounted therein adapted to be forced rearward by the powder gases, a main spring mounted in said receiver for returning said breech bolt to the closed position, a firing pin slidably mounted in said breech bolt, a spring impressed latch for locking said firing pin to said breech bolt during the reciprocating movement of said bolt, and an arm on said latch adapted to engage a cam face on the receiver for automatically releasing said firing pin and allowing it to fly forward under its own inertia when the breech bolt reaches the closed position, with a pneumatic dash pot mount-

ed at the rear end of the receiver, and adapted to arrest the rearward movement of the breech bolt, substantially as described.

15. In an automatic gun, the combination with a receiver, of a reciprocating breech bolt slidably mounted therein adapted to be forced rearward by the powder gases, a main spring mounted in said receiver for returning said breech bolt to the closed position, an extractor carried by said breech bolt, and provided with a cam face, and an ejector pivoted in said receiver, and having a short arm adapted to be struck by said cam face, substantially as described.

16. In an automatic gun, the combination with a receiver, of a reciprocating breech bolt slidably mounted therein adapted to be forced rearward by the powder gases, a main spring mounted in said receiver for returning said breech bolt to the closed position, an extractor carried by said breech bolt, and provided with a cam face, and an ejector pivoted in said receiver, and having a short arm adapted to be struck by said cam face, with a pneumatic dash pot mounted at the end of the receiver and adapted to arrest the rearward movement of said breech bolt, substantially as described.

17. In an automatic gun, the combination with a receiver, of a reciprocating breech bolt slidably mounted therein adapted to be forced rearward by the powder gases, a main spring mounted in said receiver for return-

ing said breech bolt to the closed position, a cocking arm carried by said breech bolt, and a spring impressed locking lever pivoted on said receiver and having a catch adapted to project into the path of said cocking arm and to arrest the forward movement of the breech bolt at a predetermined portion of its forward travel, with a pneumatic dash pot mounted at the end of the receiver and adapted to arrest the rearward movement of said breech bolt, substantially as described.

18. In an automatic gun, the combination with a receiver, of a reciprocating breech bolt slidably mounted therein adapted to be forced rearward by the powder gases, a main spring mounted in said receiver for returning said breech bolt to the closed position, a cocking arm carried by said breech bolt, and a spring impressed locking lever pivoted on said receiver and having a catch adapted to project into the path of said cocking arm and to arrest the forward movement of the breech bolt at a predetermined portion of its forward travel, with a latch mounted on the receiver, and adapted to hold said locking lever out of engagement with said cocking arm, when desired, with a pneumatic dash pot mounted at the end of the receiver and adapted to arrest the rearward movement of said breech bolt, substantially as described.

In testimony whereof I affix my signature. 65
WILLIAM H. PRITCHETT.
